UNITED STATES PATENT OFFICE.

HENRY S. HALE, OF PHILADELPHIA, PENNSYLVANIA.

CHAIR.

SPECIFICATION forming part of Letters Patent No. 277,272, dated May 8, 1883.

Application filed November 24, 1882. (No model.)

To all whom it may concern:

Be it known that I, HENRY S. HALE, a citizen of the United States, residing at Philadelphia, in the county of Philadelphia and State 5 of Pennsylvania, have invented certain new and useful Improvements in Chairs, of which the following is a specification, reference being had therein to the accompanying drawings.

Figure 1 is a perspective view of a chair 10 having my invention applied thereto. Fig. 2 is a perspective view, showing a modification; and Fig. 3 is a perspective view of my improved back-frame.

The object of this invention is to facilitate 15 the removal from a chair of that portion of the back which is ordinarily arranged between the two upright posts, whenever it is found desirable, to permit the backs to be conveniently repaired or beaten or otherwise cleaned.

20 Referring to the drawings, A A are the front legs, B B the rear legs, and C the seat, of the chair, which latter may be upholstered in any approved or desired manner.

D D are the posts, which in practice I usually prefer to make each in one and the same piece with the corresponding rear leg.

E E' is a girt having its ends framed into the posts D D, its upper part, E', constituting a rib or web, for a purpose which will soon be 30 explained.

F is a rod, tie-bar, or girt connecting the upper ends of the posts, and may be either a round rod, as shown, or it may consist of a square or flat bar of either wood or metal; 35 but in preference I prefer the construction shown.

As I prefer in practice to use my invention in the form shown in Figs. 1 and 3, I will first describe that figure.

40 K L M represent, respectively, the top, bottom, and one of the side rails of a back-frame, there being, of course, another side rail, M, at the opposite ends of the top and bottom rails, thus constituting a rectangular frame adapted 45 to receive and support a suitable upholstering, which may be of any usual or approved construction. The top rail, K, is provided upon its rear side with a longitudinal upwardly-inclined groove or recess, k, adapted to receive 50 the bar or girt F. The bottom rail is also re-

cessed, as at 1, to receive the upwardly-projecting rib E'.

In Fig. 2, which shows a modification of my invention, G H I I are respectively the top, bottom, and side rails of a rectangular frame, 55 and J the upholstering, the whole constituting a removable back of a chair having many features in common with the back which I have just described when referring to Fig. 3; and it will be seen that when either of these backs is 60 applied to the other parts of the chair there exist in the back of said chair two substantially rectangular frames, the removable one being supported by means of recessed bars or rails upon the cross-girts which constitute a 65 portion of the outer permanent frame of the chair.

By an examination of the drawings it will be readily understood that when either of the 70 seat-backs is supported upon the girt E E' and the girt or tie-bar F, over which the recesses are adapted to fit, the backs will be held firmly in position, and will not be liable to accidental displacement, but can be readily removed from between the posts; and it will also be seen 75 that when the construction of frame shown in Figs. 1 and 3 is employed the rib E' and tie-bar F are entirely concealed, and that, as there are no joints or open crevices in sight, the finished appearance of the chair is not 80 marred by any of the devices by means of which the removal and replacement of the back is made possible.

It will of course be understood that so far as relates to supporting the lower end of the 85 back the part E of the girt might be dispensed with, the ends of the rib E' being attached to the posts by tenons and mortises or otherwise.

Although in the drawings the ends of the 90 girt E E' and of the tie-rod F project through the posts D D, and are therefore visible, I prefer to so construct the parts that these ends do not extend through to the outer faces of the posts, or else cover them with some ornamental 95 devices.

Although I have shown my invention as applied to an ordinary four-legged and straight-backed chair of very plain design, I do not wish to be limited thereby, it being apparent 100

that it is equally well adapted for use upon other styles of chairs and the backs of various seats, such as are used in railroad-cars, street-cars, sofas, and similar articles of furniture.

5 One advantage of my invention is that it utilizes the transverse girts or tie-bars substantially such as are ordinarily employed for connecting the upper and lower ends of the back-posts.

10 Another advantage is that it utilizes the upper and lower rails with which very many chair-backs are provided by simply grooving them, as indicated in Fig. 3. Thus no increased number of parts is required beyond such as are 15 frequently found in seat-backs.

It is evident that it would be difficult to form the groove 1 except with its walls parallel to the sides of the rail L, and yet have it fit closely the rib E' and be conveniently applied thereto, and it is also apparent that it is desirable to form the girt E' in such manner that it shall serve as a part of the framework of the chair, whereas the groove k may be formed with its walls at an inclination to the sides of the rail K, and yet be conveniently applied to the girt F; hence a construction which could be advantageously used in the top rail might be practicable for the lower rail.

I do not claim herein any invention which is patented to me in my patent dated April 17, 30 1883, application for which was filed February 24, 1883, serial No. 86,112, of which this is a division.

What I claim is—

1. In a chair, the combination, with the posts 35 D D and the tie-bar or girt F, extending from post to post, of the removable back having a rectangular frame adapted to receive and support the upholstering, and being upwardly recessed to engage with the girt F, substantially 40 as set forth.

2. In a chair, the combination, with the posts D D, the tie-bar or girt F, and the girt E, provided with the upwardly-projecting rib E', of the removable back having a rectangular frame 45 adapted to receive and support the upholstering, and being upwardly recessed to engage with the upper and lower girts, substantially as set forth.

In testimony whereof I affix my signature in 50 presence of two witnesses.

HENRY S. HALE.
